COLLAR STAY DEVICE

Meyer P. Cohen, Columbia, S. C.

Application December 20, 1952, Serial No. 327,120

3 Claims. (Cl. 2-132)

1

This invention relates generally to collar stays for use with soft shirt collars, having for a principal object the provision of an improved construction of this character which is equally useful for its purpose whether the collar is closed or opened.

Another object of this invention is to provide such a collar stay construction which affords convenient means for securing collar ornaments to the collar.

Still another object of this invention is to provide such a collar stay construction which is efficient in use, economical in manufacture, simple in assembly and adjustable in length to correspond with that of the collar wing.

Other objects of the present invention will be apparent from the following description, it being understood that the present invention consists substantially in the combination, construction, location and relative arrangement of parts, as described in detail hereinafter, as shown in the accompanying drawing and as finally pointed out in the appended claims.

In the accompanying drawings:

Figure 1 is a front view of a necktie and ornamented soft short collar, the latter having applied thereto a stay construction embodying the present invention and having one wing turned up to expose part of the stay.

Figure 2 is a rear view of the construction shown in Figure 1, both wings of the collar being shown fully extended.

Figure 3 is similar to Figure 1, the collar ornament being in the form of a bar and the stay construction being modified.

Figure 4 is a rear view of the construction shown in Figure 3, both wings of the collar being shown fully extended.

Figure 5 is a section on line 5-5 of Figure 3.

Figures 6 and 7 respectively are perspective views of the collar stay members shown in Figures 1 and 3; and

Figures 8 and 9 respectively are exploded perspective views of the construction shown in Figures 1 and 3.

Referring to the drawings, and particularly to Figures 1 and 3, a stay construction embodying the present invention is shown applied, for the purpose of illustration, to the soft collar 10 of a shirt of the type commonly worn by military personnel. The collar is provided with a pair of wings 11-11 defined by an edge 12 extending generally horizontally around the collar and merging at the tips 13-13 of the wings with a pair of generally vertically extending edges

2

14-14. The collar is conventionally provided with a necktie 15.

The means for staying one wing 11 will be described, and it will be understood that the means for staying the other wing 11 is independent of, and identical to, such means. Either means comprises a stay member 16 which underlies the wing 11, and a member 17 which overlies the wing 11.

10 Referring particularly to Figure 6, the stay member 16 includes a head part 18 and a depending part 19. One of various forms that the head 18 may assume is disclosed in Patent No. 2,308,412 to Frederick A. Ballon, Jr., and Melvin W. Moore, 15 issued January 12, 1943, to which reference may be had for details. It should be here noted, however, that the head 18 is in the form of a securing device having a body member which is provided with a rim 20, a clutch as part of the 20 assembly, the clutch being provided with a pair of operable arms 21-21, and a central opening (not shown) for the reception of a prong.

The depending part 19 is in the form of a pair of relatively shiftable parts 22 and 23 constantly urged into axially extended relation by a coil spring 24. The construction and assembly of parts 22, 23 and 24 generally is the same as that of the corresponding parts disclosed in Patent No. 1,908,525 to B. B. Monaster, issued May 9, 30 1933, to which reference may be had for details. It should be here noted, however, that the part 22 is a tubular element rigidly secured, as by soldering, to the rim 20 of the body member of the head 18, being positioned thereby to extend 35 radially therefrom in depending relation thereto, and that the coil spring 24 reacts against the head 18 and not against a head formed on the tubular element 22.

The member 17 which overlies the wing 11 is in 40 the form of an ornamental button having a pair of prongs 25-25 which project from the back thereof and pierce the wing 11. For suitably securing the member 17 to the wing 11, one prong 25 is projected into the headpart 18 of the stay member 16, and the other prong 25 is projected into a securing device 26 similar in every respect to that which forms the head 18 of the stay member 16. The latter is in contracted condition and is maintained in such condition by reason of the lower extremity thereof being engaged with the wing tip 13.

In use, the ornamental button 17 is suitably positioned on the wing 11 and pressed so that the prongs 25-25 thereof pierce the material. 55 The stay member 16 is then placed in underlying

relation to the wing 11, and, by the application of finger pressure upon the arms 21-21 of the head 18, the latter is prepared to receive one of the prongs 25. The prong 25 having been projected into the head 18, the arms 21-21 of the latter are released, whereupon the prong 25 is securely clutched by the head 18. In a similar manner, the other prong 25 is projected into its securing device 26. The stay member 16 is now contracted by relative shifting of the members 22 and 23 against the force of coil spring 24. In order to maintain the member 16 in its contracted condition, the pointed lower extremity thereof is caused to pierce the wing tip 13 before the member 16 is released. Thus the coil spring 24 constantly urges the relatively shiftable parts 22 and 23 into axially extended condition so that the wing 11 is stayed against curling. For removing the stay means from the wing 11, the procedure hereinabove outlined is reversed.

Referring particularly to Figure 7, a modified form of the stay member 16 is disclosed. The head 18 shown in Figure 6 is replaced by a head part 27 which is in the form of a flat plate provided with a central opening 28. In other respects the stay members of Figures 6 and 7 are alike. In use, one prong 25 is projected through the opening 28, and then a pair of securing devices 26-26 are applied respectively to the prongs 25-25 and the stay member 16 secured in place, all in the manner hereinabove indicated.

Referring particularly to Figures 3, 4 and 9, the ornamental member may be in the form of a bar 29 which bridges the space between the collar wings 11-11, the opposite end portions thereof being disposed respectively over the latter and being provided respectively with a pair of prongs 25-25. In this event, each prong is engaged by a stay member 16 and its associated securing device 26, and there is no necessity for additional securing devices 26. The ornamental member may assume a form other than that shown. For example, it may comprise an elongated wire coil member provided with loops at opposite ends, and a pair of members each including a prong projected through one of the aforementioned loops and an ornamental head. As a further example, the ornamental member may comprise a round bar provided with opposite end portions which threadedly engage respectively a pair of ornamental members which mount prongs presenting in the same direction laterally relative to the axis of the bar.

It will be observed that the ornamental members 17 and 29 are types now generally in use, and it will be understood that either the extensible stay construction shown in Figure 6 or that shown in Figure 7 may readily be used in conjunction therewith. Furthermore, since the ornamental members are suitably positioned and the prongs thereof pressed through the wings 11 before any other step of the assembly procedure is undertaken, it should be apparent that placing the ornamental members is easy.

With regard to the embodiment of the invention shown in Figures 1 and 2, it will be observed that there is no crosstie extending between the stay members 16-16, and that for this reason the shirt collar 10 may be opened and worn in that condition without disturbing the stay members 16-16 or the ornamental members 17-17. Although the stay construction is shown applied to a shirt of the type commonly worn by military personnel, it will be understood that it is not intended to limit the present invention to such

application. In addition, it should be apparent that the member 17 may assume various geometrical forms and may be provided with only one, instead of with more than one, prong 25. Still further, it will be observed that instead of the prongs 25-25 being made a part of the ornamental member 17 and the coacting clutch a part of the stay member 16, this construction could be reversed.

It will be understood that the present invention is susceptible to various changes, modifications and applications which may be made from time to time without departing from the principles thereof and that it is intended to claim the invention broadly, as well as specifically, as indicated in the appended claims.

What is claimed as new and useful is:

1. In a stay construction for maintaining the wings of a collar in extended, uncurled condition, the combination comprising a pair of elongated members adapted to underlie respectively the collar wings, each of said elongated members including a pair of shiftable interconnected parts disposed in axially extended relation and provided respectively with a collar gripping element and a prong clutching element disposed respectively at opposite ends of said elongated member, and means for yieldably maintaining said pair of parts extended axially, and ornamental means adapted to closely overlie the collar fabric and provided with a pair of collar wing piercing prongs extending rearwardly therefrom, said pair of prongs being projected respectively into the clutch elements and being detachably clutched thereby.
2. In a stay construction for maintaining the wings of a collar in extended, uncurled condition, the combination comprising a pair of elongated members adapted to underlie respectively the collar wings, each of said elongated members including a pair of shiftable interconnected parts disposed in axially extended relation and provided respectively with a collar gripping element and a prong clutching element disposed respectively at opposite ends of said elongated member, and a coil spring wrapped around said elongated member and arranged for yieldably maintaining said pair of parts extended axially, and an elongated ornamental member the opposite end portions of which are adapted to closely overlie respectively the collar wings, each of said end portions being provided with a collar wing piercing prong extending rearwardly therefrom, said prong being projected into the associated one of said clutch elements and being detachably clutched thereby.
3. In a stay construction for maintaining the wings of a collar in extended, uncurled condition, the combination comprising a pair of elongated members adapted to underlie respectively the collar wings, each of said elongated members including a pair of shiftable interconnected parts disposed in axially extended relation and provided respectively with a collar gripping element and an apertured head disposed respectively at opposite ends of said elongated member, and a coil spring wrapped around said elongated member and arranged for yieldably maintaining said pair of parts extended axially, an elongated ornamental member the opposite end portions of which are adapted to closely overlie respectively the collar wings, each of said end portions being provided with a collar wing piercing prong extending rearwardly therefrom, and a pair of prong clutching elements, said prongs being each

freely projected through the associated apertured head aforesaid and into one of said clutch elements, being detachably clutched by the latter.
